CLAIM

The ornamental design for a cookie carrier, as shown and described.

DESCRIPTION

FIG. 1 is a top perspective view of a cookie carrier showing my new design;

FIG. 2 is a bottom perspective view thereof;

FIG. 3 is a top plan view thereof;

FIG. 4 is a bottom plan view thereof;

FIG. 5 is a front plan view thereof;

FIG. 6 is a back plan view thereof;

FIG. 7 is a left side plan view thereof; and,

FIG. 8 is a right side plan view thereof.
